(57) **CLAIM**

The ornamental design for a tape cutter, as shown and described.

DESCRIPTION

FIG. 1 is a rear perspective view of a tape cutter of the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The objects in broken lines shown in FIGS. 1, 2 and 5 are for illustrative purposes only and form no part of the claimed design.
